(57) **CLAIM**

The ornamental design for a drop counter for droppers, as shown and described.

DESCRIPTION

1. Drop counter for droppers

The design is a dropper drop-counter device consisting of a prismatic body of rectangular configuration with two major faces, a front major face showing a viewing rectangle located on the upper left side and, on its right side, a circular projection; the larger posterior face features a vertical open channel and a rectangular clip joined along a vertical longitudinal bridge in the area where the channel is not, where said clip extends horizontally until located on the channel; according to the order of the views: figure 1.1 shows a front perspective of the design, figure 1.2 shows a front elevation of the design, figure 1.3 shows the lower level of the design, figure 1.4 shows the left profile of the design, figure 1.5 shows the right profile of the design, figure 1.6 shows the upper level of the design, figure 1.7 shows the rear elevation of the design, figure 1.8 shows a rear perspective of the design, and figure 1.9 shows another rear perspective of the design.
